UNITED STATES PATENT OFFICE.

WILLIAM H. HOPE, OF PROVIDENCE, RHODE ISLAND.

PANTOGRAPH.

Application filed March 19, 1921. Serial No. 453,634.

To all whom it may concern:

Be it known that I, WILLIAM H. HOPE, a citizen of the United States, residing at Providence, in the county of Providence and 5 State of Rhode Island, have invented new and useful Improvements in a Pantograph, of which the following is a specification.

This invention relates to certain new and useful improvements in a pantograph and 10 it has for its principal object to provide an improved mechanism and construction wherein, through electrical means the cutter or cutters may be controlled by the stylus and its association to and cooperation with 15 the design, to render said cutter or cutters operative and, inoperative depending upon the nature of the contact between the stylus and the design.

The invention further resides in providing a metallic design plate coated with an 20 electrical resistance material so as to leave a design formed of this resistance material, or to have the background formed of this resistance material, and the uncoated or exposed portion of the metal plate constituting 25 the background or the design, respectively.

A further object of this invention is to provide a machine having a bed on which a metallic design plate has electrical contact, a 30 stylus for movement over or across the plate with portions of the latter coated with a resistance material, whereby electrical circuit between the bed and stylus may be made or broken according to the contact of the stylus 35 with the uncoated, or coated portions of the plate, and electrical means in circuit with the bed and stylus for raising the cutter or cutters from the work or permitting them to become operatively disposed according to 40 the particular contact being made by the stylus.

The invention also has for its object the provision of variable motion transmitting mechanism between the stylus and the cutter 45 support and between the stylus and the work support.

The invention also is found to reside in an improved pantograph construction wherein the stylus and its carriage is continuously 50 reciprocated across the design and has associated means for advancing or moving the stylus carriage step by step or intermittently in a direction transversely with respect to the reciprocatory motion of the carriage where-

by the entire design will eventually be traced 55 by the stylus in parallel, predetermined lines.

Further, the invention resides in the features of construction and the arrangements and combinations of parts described in detail in the following specification and succinctly defined in the appended claims, references being made to the accompanying drawings wherein,

Figure 1 is a front elevation of a pantograph constructed in accordance with the 65 present invention and embodying the improvements thereof;

Figure 2 is a rear elevation thereof;

Figure 3 is an end view of the pantograph; 70

Figure 4 is a detailed side elevation of a fragmental part of the mechanism employed for advancing the stylus carriage step by step, or intermittently, whereby the stylus will be caused to travel back and 75 forth across the design in fresh paths;

Figure 5 is a fragmentary view in the side elevation showing the snap switch employed;

Figure 6 is a fragmentary end view of the 80 pantograph machine looking from the opposite end from Figure 3;

Figure 7 is a detailed view of the tracing point of the stylus;

Figure 8 is a plan view of the construction shown in Figure 4; 85

Figure 9 is a similar view of the snap switch depicted in Figure 5; and

Figure 10 is a fragmentary view of an 90 improved design plate.

Referring more in detail to the drawings the numeral 1 designates the base of the machine having side standards 2 surmounting the same for supporting the superstructure hereinafter described. Between the 95 standards 2 a pair of rails 3 are mounted on the base and run forwardly and rearwardly thereof, and supported on these rails by wheels 4. is a carriage 5 which in turn supports a superposed, wheeled carriage 6 for 100 transverse movement. A forwardly extending stylus supporting arm 7 carries the stylus 8 for operating over the pattern 9 supported on the bed or platen 10. The carriage 6 is provided with a rearwardly 105 extending, grooved track 11 in which are seated wheels 12 carried on the free end of an arm extending forwardly from bracket

13, the latter being supported from a carriage 14 which traverses, on wheels 15, a track 16 in the superstructure.

An endless band 17 takes over pulleys or 5 wheels 18 journaled at opposite ends of the machine, one wheel being fixed to a worm wheel 19 that meshes with a worm 20 which derives its driving power from an electric motor 21 through the belt and pulley connections 22. A pair of electrical magnets 23 and 24 are carried by the brackets 13 in different planes to receive the respective upper and lower lengths of the band 17, said magnets having detents so that when 10 energized they will grip said band. The magnets are selectively energized in a successive manner so that only one will be operative while the other remains inoperative and by so successively engaging the upper 15 and lower portions of the band cause the carriage 14 to travel therewith back and forth over the rails 16.

The successive or alternate operations of the magnets are effected through a snap switch 25 embodying a pivoted arm 26 and a coil spring 27 which acts to quickly move the arm in opposite directions from a dead center position. The outer end of the arm is connected to the opposite ends of a flexible wire or cable 28 which is supported on the wheels or idlers 29 and has its lower length passing through a guide tube 30, the opposite ends of which alternately engage fixed stops 31 adjustably carried by the wire 35 28. Obviously, as the carriage 14 moves in one direction, the forward end of tube 30 will engage its stop 31 and move the same along therewith for effecting a pull on the wire which swings the switch arm 26 toward and 40 beyond the dead center position and thereby permits the spring 27 to reverse the switch for bringing the idle electrical magnet into play, and rendering the companion magnet inoperative, to cause a reverse travel of the 45 carriage 14.

A drum 32 is journaled on the carriage 6 and is equipped with a toothed peripheral portion 33 designed to be engaged by a dog 34 to prevent retrograde movement of the 50 drum. A cable 35 has its opposite ends secured to the drum and from there passes around pulleys 36 and 37, the same being journaled on vertical shafts on carriage 5, and on the upper end of the shaft supporting pulley 36 is fixed a pinion 38 that has meshing engagement with a rack 39 fixed relative to the base of the machine. A rack 40 is provided on carriage 5 and is traversed by a pawl 41 which is pivoted to an arm 55 42 carrying a friction pawl 43 that operates to intermittently rotate the drum 32 in one direction only.

When the carriage 6 has reached its limit of movement and reverses its motion, the 60 dog or pawl 41 will lift the arm 42 and cause

partial rotation of the drum 32 which will exert a pull on the cable 35 and thereby impart rotary movement to the pulleys 36 and 37. Obviously, rotation of pulley 36 will cause the pinion 38 to ride on the rack 39 70 and move the carriage 5 correspondingly rearwardly or forwardly. Thus it will be seen that each return movement of the carriage 6 will cause the carriage 5 to be advanced one step automatically until the 75 stylus has traced over the entire pattern.

The pattern or design plate is preferably of zinc and has the design painted thereon with an electrical resist varnish. As an example, the design 44 in Figure 10 is applied 80 to the zinc plate by painting the resist varnish thereon.

Fixedly mounted on the superstructure or track 16 is an upright arm 46 having a journal bearing shaft 47 which carries on its outer end a radially slotted wheel 48 and on its inner end a pinion 49, the latter meshing with a rack 50 carried by the upper diamond bar or carriage 51. If two sets of diamonds are employed then the pinion 49 90 will also be meshed with the rack 52 carried by a lower or second diamond bar 53. Each diamond bar is supported on respective track sections 54 by rolls or wheels 55. On the wheel 48 are a plurality of knobs 56 adjustable radially in the slots thereof whereby the knobs may be formed into a circular series that is variable in diameter. The carriage 14 is provided at its opposite ends with uprights 57 and 58 the former carrying an adjustable screw 59 and the latter carrying a reel 60. A wire or flexible member 61 has one end anchored to the screw 59 and its opposite end connected to the reel 60, the intermediate portion being looped about the circular series of knobs 56 so that when the carriage 14 is moved the flexible drive member 61 will rotate the wheel 48 and thereby impart driving movement to the pinion 49, rack 50 and diamond bar 51, 100 105 or to both racks and both diamond bars when two are employed. By varying the position of the knobs 56 in their slots the relative movement between the diamond bar in carriage 14 may be accordingly varied. Thus, the transverse tracing movement of the stylus will be increased or diminished when reproduced by the diamond points 62 on the roll 63. Each diamond point or cutter 62 is under the control of an electrical magnet 64 which when energized will effect lifting of the diamond point from the roll.

The pattern or design plate 9 is grounded electrically into the bed 10 of the machine from which the circuit passes through wire 125 45 to the serially connected electrical magnets 64, thence through wire 65 to a battery 66 and then through wire 67 and switch 68 to the stylus 8. This circuit is such that when the stylus comes in contact with the 130

- zinc plate 9 and therethrough completes the electro-magnet circuit, the magnets 64 will be energized to lift the cutters from the roll to prevent cutting of the varnish covering, and when the stylus is again moved onto any portion of the resist varnish 44 of the pattern a circuit will be broken to release the cutters for further operation on said roll.
- 10 The printing roll 63 is supported by the tail stock 69 and the head stock 70 the latter embodying a shaft 71 which carries on its outer end a fan shaped plate 72 having a counter balance 73. The plate 72 is provided with a series of radial slots in which are adjustably mounted a series of knobs 74 about which passes a flexible member 75 that has one end anchored by screw 76 to upright 77 and its opposite end connected to 20 a reel 78 journaled on upright 79, said uprights being carried on the forward and rearward sides of carriage 5.
- Stretched between uprights 77 and 79 is a rod 80 having a pair of adjustable stops 81 to be engaged by an arm 82 which is carried by the shaft extension 83 of the snap switch 25. The purpose or function of the adjustable stops 81 is to contact with the arm 82 to throw the switch in the event the 30 pull wire 28, by reason of the non-functioning of the stops 31, fails to throw said switch.
- In operation the motor 21, which may be of any suitable type operates to impart continuous movement to the belt or band 17 and through the alternate engagements by the magnets 23 and 24 a reciprocally movement is accorded the carriage 14, the limits of reciprocation being determined by the 40 position of the stops 31. Through the connection 12 and 13 the movement of carriage 14 is transmitted to carriage 6 and the stylus arm 7. Consequently the stylus will be reciprocated back and forth across the pattern or design plate and upon the start or 45 beginning of each return movement of the carriage the pawl 41 acts to lift the arm 42, swing under its pivot and permit lowering of the arm, which lowering movement will result in partially rotating the drum 32 to take up and let out the cable 35 which movement of the cable revolves the wheels 36 and 50 37 and the pinion 38 to act on the rack 39 and thereby advance the carriage 5 inwardly one step. The pawl 41 will thus drag through the greater part of each sliding movement of the carriage 6 and upon reversing this movement the pawl will swing from one side to the other of its pivotal 55 mounting and each time effect lifting of the arm 42 which automatically lowers, aided by spring 84, to partially rotate the drum. Hence it will be seen that each sliding movement of the carriage 6 is over a new or fresh 60 portion of the pattern or design. Further-
- more, each step by step advance of the carriage 5 will impart a proportionate, rotative movement to the printing roll 63 by reason of the flexible member 75, which moves with said carriage 5, winding and unwinding about 70 the series of knobs 74. The sliding movement of carriage 6 is proportionately transmitted through the diamond bar or bars, through the carriage 14, flexible member 61, wheel 48, pinion 49 and rack 50. As the 75 stylus traverses the pattern it will alternately ride over varnished and unvarnished sections and correspondingly open and close the circuit through magnet 64 to effect a lowering and lifting of the diamond cutters 80 62. Obviously then, the pattern will be reproduced accurately on the roll with lesser or greater proportions depending upon the predetermined positioning of the knobs 56 and 74.
- The current for magnets 23 and 24 may be supplied through circuit wires 85 and a battery 86. The action of the stylus is such that in the course of time it will move over the entire surface of the design in predetermined lines, and the action of the cutters will be under the control of the stylus, being lifted during each reciprocation of the carriage 6 as many times as the stylus rides off the varnished surface portions onto the unvarnished surface portions of the zinc plate, and lowered onto the roll as many times as there are portions of varnished surfaces in its path. Thus the stylus, through electrical means acts to operate the diamond cutters 90 100 either upon the roll or off the same depending wholly upon whether the design is laid in with electrical resist or whether the design is the exposed metallic plate. The operation therefore is accurate since the cutters cannot act upon the roll unless the stylus is travelling over a varnished surface.
- Having thus described my invention, what I claim as new and desire to secure by Letters Patent is:—
1. A pantograph comprising a base, a bed thereon, a carriage movable forwardly and rearwardly on the base, a stylus carriage supported on the first carriage and movable transversely thereof, a stylus supported on the second carriage for tracing a design on the bed, a superstructure on the base, a third carriage movable on the latter in a direction similar to the second carriage, a grooved rail carried by the second carriage and extending in the direction of movement of the first carriage, a bracket structure on the third carriage having a part slidable on the rail and connecting the second and third carriages for transverse movement, a continuously operating endless band, a pair of electrical magnets on the bracket having parts associated with the sectional lengths of the band and adapted to engage the respective lengths alternately whereby the second 110 115 120 125 130

and third carriages will be moved reciprocatingly, an operating circuit for the magnets including a reversible switch and a switch operating member extending along 5 side the path of movement of one of the carriages, spaced stops on said switch operating member alternately engageable by said carriage to effect a reverse throw of the switch, a printing roll support, a fan shaped plate 10 connected to the roll support and provided with radial slots, knobs adjustable in the slots, a flexible member passing about the series of knobs and having its opposite ends secured to the first carriage whereby movement of the latter will be converted and 15 transmitted to the roll support into rotary motion, a diamond bar supported for movement on the superstructure, and a variable transmission mechanism between the third 20 carriage and the diamond bar.

2. In a pantograph, a diamond cutter, electrical means for moving the cutter out of cutting position, a stylus, a design embodying a metallic plate having portions of its 25 surface covered with an electrical resistance material, and a circuit including said means, said design plate and said stylus, adapted to be closed by direct contact between the stylus and the exposed portion of the plate.

30 3. In a pantograph, a cutter, a stylus, a design plate of metallic body having portions covered with a resistance element, and means for moving the cutter out of cutting position when the stylus is in contact with 35 one portion of the plate and for permitting movement of the cutter to cutting position when the stylus is in contact with another portion of the plate.

4. In a pantograph, a cutter, an electro- 40 magnet for lifting the cutter from its work, a stylus, a metallic design having portions exposed for direct contact with the stylus, and an electric circuit connected on one side to the stylus and on the other side to the 45 design and including said magnet.

5. In a pantograph, a cutter, a movable support therefor, a stylus, means for converting the movement of the stylus into a different movement for the cutter support, 50 and electrical means under the control of the stylus for moving the cutter out of cutting position.

6. A pantograph comprising a base, a bed 55 thereon, a carriage movable forwardly and rearwardly on the base, a stylus carriage supported on the first carriage and movable transversely thereof, a stylus supported on the second carriage for tracing a design on the bed, a super-structure on the base, a 60 third carriage movable on the latter in a direction similar to the second carriage, a grooved rail carried by the second carriage and extending in the direction of movement of the first carriage, a bracket structure on the third carriage having a part 65 slideable on

the rail and connecting the second and third carriages for transverse movement, a continuously operating endless band, a pair of electrical magnets on the bracket having parts associated with the sectional lengths 70 of the band and adapted to engage the respective lengths alternately whereby the second and third carriages will be moved reciprocatingly, an operating circuit for the magnets including a reversible switch and 75 a switch operating member extending along side the path of movement of one of the carriages, spaced stops on said switch operating member alternately engageable by said carriage to effect a reverse throw of the 80 switch, a work support, a cutter, and means for converting the movement of the stylus carriage into predetermined motion for the cutter.

7. A pantograph comprising a base, a bed 85 thereon, a carriage movable forwardly and rearwardly on the base, a stylus carriage supported on the first carriage and movable transversely thereof, a stylus supported on the second carriage for tracing a design on 90 the bed, a super-structure on the base, a third carriage movable on the latter in a direction similar to the second carriage, a grooved rail carried by the second carriage and extending in the direction of movement 95 of the first carriage, a bracket structure on the third carriage having a part slideable on the rail and connecting the second and third carriages for transverse movement, a continuously operating endless band, a pair of 100 electrical magnets on the bracket having parts associated with the sectional lengths of the band and adapted to engage the respective lengths alternately whereby the second and third carriages will be moved reciprocatingly, an operating circuit for the 105 magnets including a reversible switch and a switch operating member extending along side the path of movement of one of the carriages, spaced stops on said switch operating member alternately engageable by said carriage to effect a reverse throw of the 110 switch, a printing roll support, a variable transmission mechanism between the roll support and the first carriage, a diamond bar supported for movement on the superstructure, and a variable transmission mechanism between the third carriage and the diamond bar.

8. In a pantograph, a stylus, a cutter, and means for transforming the motion of the stylus to that of the cutter, said means including a rotary member having radial slots, a series of knobs adjustable in the slots, and a flexible member connected at its ends to 125 one of said first two elements and having its intermediate portion looped about the series of knobs, said rotary member being connected to the other of said first two elements.

9. In a pantograph, a stylus, a cutter, and means for transforming the motion of the stylus into that of the cutter, said means including a rotary member carried by one of said first two elements, a variably diametered part carried by the member, and a flexible member connected to the other of said first two elements and engaged about said part.
10. In a pantograph, a carriage supporting the same, a cutter support, variable transmission means between the carriage and the support, a work support, variable transmission means between the latter and the carriage, each of said means including a rotary member having radially adjustable projections and a flexible member passing about the projections and connected to the stylus carriage, the rotary members being connected to the work and cutter supports.
11. In a pantograph a continuously moving endless band, a reciprocatory carriage, electrical means carried by the latter for alternately engaging the two flights of the band to move the carriage back and forth, a stylus connected to the carriage for movement therewith, and means for advancing the stylus step by step over a design as it is traced by its reciprocatory motion.
12. In a pantograph, a frame, a carriage movable thereon, a stylus carriage movable back and forth across the first carriage, and means for advancing the first carriage intermittently by and during reciprocation of the second carriage.
13. In a pantograph, a frame, a carriage movable thereon, a stylus carriage movable back and forth across the first carriage, a fixed rack on the frame, a pinion on the first carriage cooperating with the rack to advance said carriage, and means for intermittently rotating the pinion.
14. In a pantograph, a frame, a carriage movable thereon, a stylus carriage movable back and forth across the first carriage, a fixed rack on the frame, a pinion on the first carriage cooperating with the rack to advance said carriage, means on the second carriage to rotate the pinion, and means on the first carriage cooperating with the aforesaid means to effect intermittent movement thereof by and during movement of the second carriage.
15. In a pantograph, a frame, a carriage movable thereon, a stylus carriage movable back and forth across the first carriage, a fixed rack on the frame, a pinion on the first carriage cooperating with the rack to advance said carriage, means on the second carriage to rotate the pinion including a rotating member, a pawl and ratchet mechanism for rotating the latter, a lever arm for the mechanism, a reversible pawl on the free end of the arm, and a rack on the first carriage engageable by the reversible pawl to oscillate the arm by and during movement of the second carriage to impart intermittent movement to the mechanism and pinion.
16. In a pantograph, a design plate having electrically conductive and non-conductive surface portions, a cutter, means for rendering the latter operative and inoperative and including an electrically operative element, a stylus, and a circuit including the latter, the element, and the conductive surface portion of the design plate and adapted to be closed upon bringing the stylus into contact with the conductive surface portion of the design plate.
17. In a pantograph, a frame, a carriage movable thereon, a stylus carriage movable on the first carriage, means having oppositely moving parts for reciprocating the stylus carriage, electrical means on the stylus carriage for operatively engaging said parts alternately to effect such reciprocation, and a cutter operable by the movement of the stylus carriage.
18. In a pantograph, a frame, a carriage movable thereon, a stylus carriage movable on the first carriage, means having oppositely moving parts for reciprocating the stylus carriage, electrical means on the stylus carriage for operatively engaging said parts alternately to effect such reciprocation, a reverse switch for controlling said electrical means, an endless switch-throwing member embodying spaced stops for cooperating with the reciprocatory movements of the stylus carriage to effect the throwing of the switch, and a cutter controlled by the stylus carriage.
19. In a pantograph, a cutter, electrical means for lifting the cutter from its work, a stylus, and a circuit including said means and adapted to be closed through the stylus when the latter is operatively disposed.
20. In a pantograph, a work support, means for oscillating said work support, a stylus carriage, a second carriage supporting the stylus carriage and embodying spaced stops, means under the control of the second carriage for imparting oscillating movement to the work support by and during movement of said second carriage, means for reciprocating the stylus carriage, said last means having a part engageable by said stops for controlling its operation, a cutter, and means for converting the motion of the stylus carriage into a predetermined motion for the cutter.
21. A design plate for the electrical control of the cutter of a pantograph, comprising electrically conductive and non-conductive surface portions, one portion forming the design and the other portion its background.
22. In a pantograph, a bed, a stylus movable thereover, a stylus carriage supported for universal movement, a work support,

electrically operated cutters for operating on the work in said support, a carriage supporting the cutters, means connecting the cutters and stylus in circuit through a pattern on the bed, and means for transmitting the motion of the stylus carriage to the work support.

23. In a pantograph, a bed, a stylus carriage supported for movement forwardly and rearwardly and laterally relative thereto, a stylus on the carriage for tracing a design on the bed, a work support, a diamond bar supported for movement relative thereto, a cutter on the diamond bar, and means operable by the stylus carriage during its forward and rearward movements for moving the work support.

24. In a pantograph, a bed, a stylus carriage supported for forward and lateral movements relative thereto, a work support embodying a shaft, a cutter controllable by the stylus on said carriage, a radially slotted member secured to said shaft, a series of projections adjustable in the slots of said member, and a flexible motion-transmitting member taking about said series of projections and having its ends connected to the stylus carriage whereby upon forward movement of the latter the flexible member will wind and unwind to impart rotary movement to the shaft.

25. In a pantograph, a bed, a stylus carriage movable lengthwise and laterally thereof, a work support, a cooperating cutter controllable by the stylus, and mechanism for transmitting the movement of the stylus carriage in one direction to the cutter including a cutter carriage, and a third carriage intermediate to cutter and stylus carriages, and variable speed transmission means connecting the cutter and intermediate carriages.

26. In a pantograph, a bed, a stylus carriage movable lengthwise and laterally thereof, a work support, a cooperating cutter, a carriage supporting the cutter and embodying a tooth portion, a pinion meshing with said tooth portion, a rotatable member with which said pinion is connected and provided with an expansible and contractible rim portion, a flexible member taking about the rim portion to have rolling contact therewith, and a support movable by the stylus carriage and having the ends of the flexible member anchored thereto.

27. In a pantograph, a bed, a stylus carriage movable lengthwise and laterally thereof, a work support, a cooperating cutter, a carriage supporting the cutter, an intermediate carriage between the first two carriages, variable motion - transmitting means connecting the intermediate and cutter carriages, and means for imparting the lateral movements of the stylus carriage to the intermediate carriage.

28. In a pantograph, a bed, a stylus carriage movable lengthwise and laterally thereof, a work support, a cooperating cutter, a carriage supporting the cutter, an intermediate carriage between the first two carriages, variable motion-transmitting means connecting the intermediate and cutter carriages, and means for imparting the lateral movements of the stylus carriage to the intermediate carriage including an automatic reversing mechanism.

29. In a pantograph, a bed, a stylus carriage movable lengthwise and laterally thereof, a work support, a cooperating cutter, a carriage supporting the cutter, an intermediate carriage between the first two carriages, variable motion - transmitting means connecting the intermediate and cutter carriages, and means for imparting the lateral movements of the stylus carriage to the intermediate carriage including a bracket mounted on one carriage and having a sliding connection with the other carriage, and means for moving the stylus carriage embodying an endless drive member, and means carried by the bracket for selectively engaging either flight of the endless member.

30. In a pantograph, a bed, a stylus carriage movable lengthwise and laterally thereof, a work support, a cooperating cutter, a carriage supporting the cutter, an intermediate carriage between the first two carriages, variable motion - transmitting means connecting the intermediate and cutter carriages, and means for imparting reciprocatory motion to the stylus and intermediate carriages.

31. In a pantograph, a bed, a stylus carriage movable laterally and lengthwise thereof, a work support, a cutter cooperating therewith, means for reciprocating the stylus carriage in one direction, and means operable by the carriage for intermittently imparting movement to the carriage at an angle to such reciprocatory motion.

32. In a pantograph, a bed, a stylus carriage movable laterally and lengthwise thereof, a work support, a cutter cooperating therewith, and means for reciprocating the carriage in one direction and moving it step by step transversely of such reciprocatory movement.

33. In a pantograph, a bed, a stylus carriage movable laterally and lengthwise thereof, a work support, a cutter cooperating therewith, a drive mechanism including oppositely moving parts, and means for alternately engaging said parts to effect reciprocation of the carriage.

34. In a pantograph, a bed, a stylus carriage movable laterally and lengthwise thereof, a work support, a cutter cooperating therewith, a drive mechanism including oppositely moving parts, means connected to

the carriage and alternately engageable with said parts to effect reciprocation of the carriage, and means operable by the carriage to effect such alternate engagement.

5 35. In a pantograph, a bed, a stylus carriage movable laterally and lengthwise thereof, a work support, a cutter cooperating therewith, a drive mechanism including oppositely moving parts, and electrical 10 means for alternately connecting the carriage to said parts.

36. In a pantograph, a bed, a stylus carriage movable laterally and lengthwise thereof, a work support, a cutter cooperating 15 therewith, a drive mechanism including oppositely moving parts, electro-magnets connected to the stylus carriage and each adapted to engage a respective part of said drive mechanism, and means under the control 20 of the carriage for effecting alternate functioning of the electro magneto.

37. In a pantograph, a bed, a stylus carriage movable laterally and lengthwise thereof, a work support, a cutter cooperating 25 therewith, a drive mechanism including oppositely moving parts, clutch devices movable with the carriage and associated with the respective parts of the drive mechanism to engage said parts, and means for 30 alternately operating the clutch devices.

38. In a pantograph, a bed, a stylus carriage movable laterally and lengthwise thereof, a work support, a cutter cooperating 35 therewith, a drive mechanism including oppositely moving parts, clutch devices movable with the carriage and associated with the respective parts of the drive mechanism to engage said parts, electrical means for alternately operating the 40 clutch devices including a switch, and means placing the switch under the control of the carriage by and during movement thereof.

39. In a pantograph, a bed, a stylus carriage movable laterally and lengthwise 45 thereof, a work support, a cutter cooperating therewith, a drive mechanism including oppositely moving parts, clutch devices movable with the carriage and associated with the respective parts of the drive mechanism to engage said parts, electrical means 50 for alternately operating the clutch devices including a switch, a switch operating member, and adjustable stops thereon for engagement by the carriage at its opposite 55 limits of movement for operating the switch.

40. In a pantograph, a bed, a stylus carriage movable laterally and lengthwise thereof, a work support, a cutter cooperating 60 therewith, a drive mechanism including oppositely moving parts, clutch devices movable with the carriage and associated with the respective parts of the drive mechanism to engage said parts, means for alternately operating the clutch devices, and means for moving the carriage step by 65

step transversely of the path of reciprocation thereof.

41. In a pantograph, a bed, a stylus carriage movable laterally and lengthwise thereof, a work support, a cutter cooperating therewith, a drive mechanism including oppositely moving parts, clutch devices movable with the carriage and associated with the respective parts of the drive mechanism to engage said parts, means for alternately operating the clutch devices, a 70 rack extending transversely of the path of reciprocation of said carriage, a pinion meshing with said rack, and means operable by and during the reciprocation of said carriage for imparting intermittent rotary movement to the pinion to effect a corresponding movement of the carriage transverse to its path of reciprocation.

42. In a pantograph, a bed, a stylus carriage movable laterally and lengthwise thereof, a work support, a cutter cooperating therewith, a drive mechanism including oppositely moving parts, clutch devices movable with the carriage and associated 90 with the respective parts of the drive mechanism to engage said parts, means for alternately operating the clutch device, means for intermittently moving the carriage transversely of the reciprocatory path 95 thereof by and during such movements, said means embodying a part movably carried by the carriage, a toothed member extending along the path of reciprocation, and a pawl carried by said movable part for trailing over said toothed member and adapted to engage with a tooth thereof upon the beginning of each reciprocation to raise said movable part and move thereunder to again trail over said toothed member and by raising said movable part to effect such transverse movement of the carriage.

43. In a pantograph, a bed, a stylus carriage movable laterally and lengthwise thereof, a work support, a cutter cooperating 110 therewith, a drive mechanism including oppositely moving parts, clutch devices movable with the carriage and associated with the respective parts of the drive mechanism to engage said parts, means for alternately operating the clutch device, a second carriage supporting the stylus carriage for reciprocatory movement and movable itself in a transverse direction, said second carriage having a toothed portion extending along the path of movement of the stylus carriage, a swinging pawl trailing over the toothed portion and engageable therewith to pivot thereon at the beginning of each reciprocation of the stylus carriage, 115 an arm pivoted on the stylus carriage and pivotally supporting the pawl, a drum journaled on the arm, means for imparting rotary movement to the drum upon upward and downward oscillation of the arm ef- 120 125 130

fected through the swinging of the pawl beneath its pivotal mounting, an endless cable taking about the drum, a pulley journaled on the second carriage and about 5 which the cable passes, a pinion connected to the pulley, and a rack meshing with the pinion and extending in the direction of movement of the second carriage.

44. In a pantograph, a bed, a stylus carriage movable laterally and lengthwise thereof, a work support, a cutter cooperating therewith, a drive mechanism including oppositely moving parts, clutch devices movable with the carriage and associated 10 with the respective parts of the drive mechanism to engage said parts, means for alternately operating the clutch device, a second carriage supporting the stylus carriage for reciprocatory movement and movable itself 15 in a transverse direction, and means carried by in part and operable by and during movement of the stylus carriage for moving the second carriage.

45. In a pantograph, a bed, a stylus carriage movable laterally and lengthwise thereof, a work support, a cutter cooperating therewith, a drive mechanism including oppositely moving parts, clutch devices movable with the carriage and associated with 20 the respective parts of the drive mechanism to engage said parts, electrical means for alternately operating the clutch devices including a switch, a second carriage supporting the stylus carriage for reciprocatory movement and movable itself in a transverse 25 direction, and spaced stops arranged on the second carriage for controlling the switch.

46. In a pantograph, a bed, a stylus carriage movable laterally and lengthwise thereof, a work support, a cutter cooperating therewith, a drive mechanism including oppositely moving parts, clutch devices movable with the carriage and associated with the respective parts of the drive mechanism to engage said parts, electrical means for alternately operating the clutch devices including a switch, a second carriage supporting the stylus carriage for reciprocatory movement and movable itself in a transverse 40 direction, spaced stops on the second carriage, and an arm connected to the switch and extending between stops.

47. In a pantograph, a bed, a stylus carriage movable laterally and lengthwise thereof, a work support, a cutter cooperating therewith, a drive mechanism including oppositely moving parts, clutch devices movable with the carriage and associated with the respective parts of the drive mechanism to engage said parts, electrical means for alternately operating the clutch devices including a switch, a second carriage supporting the stylus carriage for reciprocatory movement and movable itself in a transverse 45 direction, spaced stops on the second carriage, and motion transmission means connecting the second carriage to the work support.

In testimony whereof I have signed my name to this specification in the presence of two subscribing witnesses.

WILLIAM H. HOPE.
